HUMIDIFIER

George R. Siefken, New York, N. Y.

Application January 24, 1941, Serial No. 375,773

8 Claims. (Cl. 299—20)

This invention relates to humidifiers, such as are commonly employed in association with heating apparatus to introduce moisture into the atmosphere of a room, and is concerned more particularly with a novel humidifier which is highly efficient in operation and is inexpensive to construct and maintain. The new humidifier may take various forms and, since it may be used to special advantage in connection with a steam or similar radiator, a construction suitable for that purpose will be illustrated and described in detail for purposes of explanation.

The new humidifier includes an open top vessel, which is preferably long and relatively narrow and holds a supply of water which may be replenished from time to time or be maintained at a selected level by a supply pipe provided with a conventional float-controlled valve. A plurality of plate-like humidifying elements are mounted above the vessel with each element having a portion entering the liquid and the elements may be advantageously threaded on a supporting rod so that they lie face to face in spaced relation. The elements are of such dimensions as to project outwardly beyond the side walls of the vessel and, if desired, the latter may include a pair of spaced extensions above each of which a series of elements is mounted. A perforated cover overlies the elements.

Each element includes one or more plates of porous material having an extension therefrom which enters the liquid, and fibrous material, such as blotting paper, may be advantageously used for the plates and extensions. Since the elements absorb water from the vessel, each face of each plate serves as an evaporating surface and since the plates lie close together and each may have a face area of considerable size, the total evaporating surface of a relatively small group of plates may be many times that of the surface of the liquid in the vessel. When the humidifier is mounted above a radiator, the air rising therefrom passes between the plates to take up moisture and flows out through the openings in the cover. As the plates are closely spaced and thin streams of air flow across their surfaces, highly effective humidification results.

For a better understanding of the invention, reference may be had to the accompanying drawing in which

Fig. 1 is a longitudinal vertical section through one form of humidifier of the invention;

Fig. 2 is a sectional view on the line 2—2 of Fig. 1;

Fig. 3 is an enlarged sectional view on the same line as Fig. 1;

5 Fig. 4 is a sectional view, similar to Fig. 3, of a modified construction;

Fig. 5 is a partial sectional view of a modified form of the new humidifier; and

Fig. 6 is a sectional view on the line 6—6 of one of the plates shown in Fig. 5.

The humidifier in the form illustrated comprises a vessel 10 which may be of sheet metal and is mounted on top of a radiator of which portions 11 only are shown. The vessel may conveniently include a reservoir section 12 at one end extending the full width thereof and a pair of troughlike extensions 13 leading from one end of the reservoir. These extensions are separated by an opening 14 defined by the inner walls 15 of the extensions, an end wall 16 of the reservoir, and an end wall 17 which closes the ends of the extensions. The end wall 17 and a wall 18 at the end of the reservoir opposite that from which the extensions lead, rise a substantial distance above the top of the reservoir and extensions, and each wall is provided with an inwardly turned flange 19 on which a cover 20 rests and is held in place by thumb screws 21.

30 Mounted on the inner face of each of the walls 17, 18 is a bracket 22 having pairs of slots in its upper surfaces. The slots in the brackets are in alignment and rods 23 are supported in opposed slots in the two brackets.

35 Each rod lies above one of the extensions 13.

A plurality of evaporating elements are mounted on those portions of the rods overlying the extensions and, in the construction illustrated in Fig. 1, each evaporating element 40 comprises a pair of plates 24 of porous material which are of square shape. There is an opening near one corner of each plate and between the plates near the corner is a spacing block 25 having an opening in alignment with 45 the openings through the plates, the block being secured in position in any suitable manner, as by means of a staple 26 passing through the plates and block. The rod 23 passes through the openings so that the unit depends from the rod and the size of the plate is such that one corner 27 enters the extensions of the vessel below the rod.

50 The plates may have integral extensions from their lower ends entering the liquid in the extensions of the vessel, but, for economy in

manufacture, a tab 28 of porous material is mounted between the plates at their lower corners and is held in place by a staple 29, the tab being of the same thickness as the spacing block 25. Other spacing blocks 30 are mounted between the plates at the remaining corners and are held in place by staples 31. Between each unit and the adjacent unit, a spacing washer 32 is mounted on the rod and that portion of each rod which overlies an extension 13 carries a full complement of the units.

The plates 24 and the tabs 28 are made of porous material so that the liquid will rise therein by capillary action and ultimately saturate the entire element. Blotting paper of a good grade is satisfactory and an available paper of this sort has sufficient strength to permit handling while wet.

The plates of the evaporating elements are of such size, that when they are mounted on the rods, they extend outwardly beyond the trough-like extensions a substantial distance, and the corners of the plates thus overlie the opening 14 between the extensions. The cover 20 is of a shape to conform to the edges of the plates and has downwardly extending flanges 33 and a number of openings 34 therethrough.

When the humidifier is mounted on a radiator, the upwardly rising current of air from the radiator flows through the opening 14 and also enters the space beneath the cover between the outer walls of the vessel and the flanges 33. The air passes between adjacent plates and escapes through the openings in the cover, and in its travel, it flows between the closely spaced plates so as to take up moisture therefrom. Since there are a large number of plates, the total evaporating surface which they provide is such that an excellent humidifying effect is obtained.

After the humidifier has been in use for a period of time, particles of dust may have collected on the surfaces of the plates to such an extent that the latter must be cleaned. For this purpose, the cover is removed and the rods with the humidifying elements thereon are lifted free of their supports. The elements are then slipped off the ends of the rods and may be washed and cleaned. The plates are then restored to the rods and the latter put back in their supports and the cover replaced.

The humidifying elements shown in Fig. 4 are similar to those above described, except that each element comprises a single plate 35 of porous material provided with spacing blocks 36 held in place by staples 37 and each plate is provided with a tab 38 which enters the liquid.

In Fig. 5, there is illustrated a modified form of the humidifier similar in all respects to that above described, except that instead of a single rod 23 for each group of plates, three rods 39 are provided. The rods 39 are supported on the end walls 18 of the vessel on brackets 22a similar to the brackets 22 and between adjacent plates 40 threaded on the rods are spacing washers 41. Each plate has attached to its lower end by a staple 42 a pair of similar extensions 43, these extensions being at opposite faces of the plate.

By constructing the vessel with a reservoir section, the liquid may be replenished without difficulty upon removal of the cover. Also, the use of the reservoir section makes it possible to provide an automatic water supply, including a valve controlled by a float in the reservoir.

I claim:

1. A humidifier comprising a vessel containing liquid, said vessel having opposite walls extending above the level of the liquid, a rod detachably mounted on said walls above the liquid, a plurality of plates of porous material threaded on the rod and lying face to face, said plates having portions entering the liquid, and spacers on the rod separating adjacent plates.
- 5 10 15 20 25 30 35 40 45 50 55 60 65 70 75 2. A humidifier comprising a vessel containing liquid, said vessel having opposite walls extending above the level of the liquid, a plurality of plates of porous material, a mounting for said plates above the liquid including a rod on which the plates are threaded near their upper ends so that the plates lie face to face, spacers on the rod separating adjacent plates, and means for detachably mounting said rod on said walls above the liquid, said plates having portions at their lower ends dipping into the liquid and the plates being suspended from said mounting and supported solely thereby.
3. A humidifier comprising a vessel having a pair of trough-like portions lying parallel and spaced apart and containing liquid, said vessel having opposite walls extending above the level of the liquid, a rod detachably mounted on said walls above each trough and above the liquid therein and extending longitudinally of the trough, and a plurality of plates of porous material threaded on and suspended from each rod and lying in spaced relation, said plates having portions entering the liquid in said trough-like portions of the vessel.
4. A humidifier comprising a vessel having a trough-like portion containing liquid, a series of plates of porous material lying face to face in spaced relation, each of said plates being rectangular in shape and so disposed that one corner points upwardly, a mounting for the plates above said trough-like portion including a rod passing through the upper corners of the plates, said plates having portions at their lower ends dipping into the liquid, and the lateral corner portions of the plates projecting laterally over and beyond the side walls of said trough-like portion of the vessel.
5. A humidifier comprising a vessel having a trough-like portion containing liquid, a series of plates of porous material lying face to face in spaced relation, each of said plates being square in shape and so disposed that one corner points upwardly, a mounting for the plates above said trough-like portion including a rod passing through the upper corners of the plates, each of said plates having a square shaped tongue of porous material attached to the lower corner of the plate and dipping into said liquid, and the lateral corner portions of each plate projecting laterally over and beyond the side walls of said trough-like portion of the vessel.
6. A humidifier comprising a vessel having a pair of trough-like portions lying parallel and spaced apart and containing liquid, a series of plates of porous material lying face to face in spaced relation above each trough-like portion, said plates being rectangular in shape and so disposed that one corner points upwardly, mountings for the plates above the trough-like portions, each mounting including a rod which passes through the upper corners of the plates of one series, the lower ends of the plates having portions which dip into the liquid in said trough-like portions and the lateral corner portions of the plates of each series projecting laterally over and

beyond the side walls of the corresponding trough-like portion of the vessel.

7. A humidifier in accordance with claim 6 in which said vessel has opposite walls extending above the level of the liquid and in which said rods are detachably mounted on said walls, and a perforated cover overlying the plates and detachably supported by said walls, said cover having portions inclined to conform with the inclination of the upper outer edges of the two series of plates.

8. A humidifier comprising a vessel having a trough-like portion containing liquid, a plurality of plates of porous material lying face to face in

spaced relation, each of said plates being rectangular in shape and so disposed that one corner points upwardly, a mounting for the plates above said trough-like portion, said mounting comprising at least three rods one of which passes through the upper corners of the plates and the other two of which pass through the lateral corners of the plates, said vessel having opposite walls extending above the level of the liquid, and means for detachably mounting said rods on said walls, each of said plates having a portion at its lower end which enters the liquid.

GEORGE R. SIEFKEN.
